UNITED STATES PATENT OFFICE

VALERIUS POMERNACKI, OF CHICAGO, ILLINOIS

DESIGN FOR AN AQUARIUM

Application filed June 22, 1931. Serial No. 40,297. Term of patent 7 years.

To all whom it may concern:

Be it known that I, VALERIUS POMERNACKI, a citizen of the United States of America, residing at Chicago, in the county of Cook and State of Illinois, have invented a new, original, and ornamental Design for Aquarium, of which the following is a specification, reference being had to the accompanying drawings, forming part thereof.

I claim:

The ornamental design for an aquarium, as shown.

VALERIUS POMERNACKI.
